ROLL-BEARING DEVICE

Sven Erik Malte Norlindh, Hallefors, Sweden

Application May 11, 1944, Serial No. 535,148
In Sweden May 21, 1943

3 Claims. (Cl. 80—31.1)

1

The present invention relates to a roll bearing device, preferably for rolling mills, and has for its object to improve the usual roll bearing or, more strictly speaking to replace them by a construction, which is less bulky, provides better possibilities of mounting of the rolls and enables a more rapid exchange of rolls; the new construction having the important advantage that the rolling pressure is unloaded from the frame and is instead transferred from one bearing box directly to the other via so-called stay-screws.

The construction is also intended to utilize as much as possible the advantages which may be obtained by use of roller bearings and other exactly made bearing constructions. Essentially characteristic for the construction is i. a. that posts have been substituted for the roll casings, which posts support and guide the bearing boxes. The construction as a whole and its different features may be said to be based on this constructional detail, as will be seen from the following.

The invention is illustrated by way of example in the accompanying drawings, which relate to two different rolling mills. Thus Figs. 1-7 relate to two high mills and Figs. 8, 9 and 10 to three high mills.

Fig. 1 shows a section I—I of the pair of rolls of Fig. 2, while Fig. 2 shows a front view of the pair of rolls.

Fig. 3 shows a section along the broken line III—III of Fig. 1 with some parts added.

Fig. 4 shows an end view of a pair of rolls carried by its posts and Fig. 5 a front view of two pairs of rolls of the reciprocating two high mill, which are mounted in a similar manner.

Fig. 6 shows a pair of rolls in a radial section and Fig. 7 a detail section along the line VII—VII of Fig. 6.

Fig. 8 shows a front view of the three high mill rolls and Fig. 9 in the left half a radial section and in the right half an end view of the three high mill rolls.

Fig. 10 shows a plan view of three high mill roll pairs without adjusting device for the rolls.

In all of the figures the top, intermediate and bottom rolls are designated by 1, 1a and 2 respectively and their bearing boxes with 3, 3b and 4, respectively. The mounting of the rolls is seen in Fig. 3, the upper section of which shows the known SKF-construction with spherical roller bearings 5 for the roll journals 3a, two for each journal. The journal situated to the left has a shoulder and the narrower outer part of it is resting in a roller bearing provided with a divided 55

outer ring 5a guiding the rolls in the axial direction.

The bearing boxes are supported and guided by posts 6 (Figs. 3, 4 and 5), each resting on a separate base plate 7. Each post with its base plate is used instead of a bearing casing and is according to the invention provided with a guide, in the first place for the two bearing boxes, which are situated at the same side of the pair of rolls 10 and of the post. The post, however, can at the same time form a guide at its other side for the bearing boxes of another pair of rolls, for instance in two high mills according to Fig. 3, in which the post has a T-profile, the flanges 8 constituting the guides themselves. Posts intended to guide only at one side may for instance have L-profile. In the bearing boxes there are recesses 9 corresponding to the flanges. Due to these flanges and recesses the bearing boxes and the rolls will obtain 15 a good guidance. Of course, this guiding device may also be made in other manners. The bearing boxes 3, 4 respectively at each side are connected to each other by means of two stay-screws 12 (Fig. 1). By means of a head 13 on the screw 15 and a bushing 14 fixed in the lower bearing box 4 each stay-screw is fastened in this bearing box, and by means of a nut 10, fixed in the upper bearing box 3 and provided with screw threads for the stay-screw, a screw connection is obtained which 20 enables the desired change of the distance between the rolls. Because of the fact that the nut 10 of the stay-screw has been placed in close proximity of the bushing 14, that part of the stay-screw which transfers the rolling pressure will become very short and consequently the resilience 25 will be small, which fact is of decisive importance for narrow tolerances of rolled material. In Fig. 1 the reference numeral 15 designates distance bars and 16 and 17 an elastic suspension of the top roll, which eliminates the play in the threads and at the head 13 of the stay-screws.

The stay-screws are synchronised by, for instance, a worm gear 18, 19 which is adapted to be turned by means of a handwheel 20, Figs. 4 and 5, or by an electric motor.

In Fig. 5 the bottom roll of the pair of rolls to the right is stationary, that is to say that its bearing boxes rest in the post for instance on adjusting screws 22, and may be immobilized by 50 means of screw bolts 23. The top roll 1 consequently can be raised and lowered. At the pair of rolls to the left the case is opposite. Here the top roll 1 is stationary and the bottom roll 2 is adjustable as to the height, that is to say it hangs in the stay-screws 12.

3

The stay-screws 12 have their upper ends united by a yoke 24, which is provided with a hook or the like 25 by which the rolls and bearing box assembly may be handled by a crane when it is to be lowered into or lifted from the posts in the fully assembled state. This is a great advantage because sets of rolls thereby may be exchanged for others which have been mounted and mutually adjusted and provided with conducting devices and cooling water tubes, before they are lowered into place upon the posts.

The bars 26, 27 (Figs. 3, 6), which carry the conducting devices on the ingoing and outgoing sides (see Fig. 6) 28, 29 respectively, are for instance by means of bolts 30 (Fig. 3) fixed directly in the bearing boxes, thus following the rolls, when the latter are to be adjusted.

If the conducting devices consist of separate lower scrapers and separate upper scrapers, it is not necessary to adjust the conducting devices when the position of the rolls is changed. This is especially important in fore-pairs with adjustable bottom roll, in which adjustment often must be done and in which the conducting device on the outside only consist of lower scrapers.

Also the bars 32, 34 (Fig. 6), which carry the cooling water tubes 35, are fixed directly in the bearing boxes. All of the bars connect the bearing boxes in such a manner that the axial adjustment will become more exact than with roll bearing devices, which are hitherto usually employed. This axial adjustment is done by means of screws 37 (Figs. 3 and 5). As will be seen from the figures the screw heads act upon the web of the posts. The construction is quite satisfactory also when the stay-screws are set by means of a motor between each pass, the screws in such case being provided with lock nuts (Fig. 10). In order to enable axial adjustment of one roll relatively to the other the bushing 14 in Fig. 3 is provided with expansion holes in the length direction of the rolls.

The bearing boxes will not be so broad as a roll housing whereby the conducting devices become more easily accessible and it will be easier to control that the conducting devices are correctly positioned. The posts have been made unilateral, that is to say that they are located at only one side of the rolls, note Figs. 3, 4 and 6, whereby the couplings between the rolls are accessible from one side.

The cooling water supply tubes may be mounted in the posts and the cooling water tubes 35 in Figs. 6 and 7 may be provided with fixed splash plates 38. Thus loose protection plates, wood blocks, waste and other provisional splash plates may be obviated. For the sake of simplicity roll grooves, if such exist, are shown only in Fig. 7.

In a twin high mill the middle roll series is fixed as to the height whereby universal couplings may be obviated in this case, besides which the distance between the pairs of rolls may be reduced which is advantageous when repeaters are used. In Fig. 5 the middle roll series is represented by the bottom roll to the right and the top roll to the left. Its coupling necks are connected by means of a coupling at 39, see Fig. 3.

As the cooling water tubes also lighting conductors with contact plugs for flexible conductor lamps may be fixed in the post.

As has been already said the posts have been formed with guiding surfaces, so that the pairs of rolls may be completely mounted and provided with conducting devices and cooling water supply tubes outside the train. The exchange of rolls

4

therefore will become very easy and quick and is done as follows:

- (a) The roll couplings are dismounted,
- (b) The supply of cooling water is shut off,
- (c) The old pair of rolls is lifted off,
- (d) The new pair of rolls is pushed in ready state on the posts,
- (e) The roll couplings are mounted,
- (f) The cooling water is supplied again.

In the case of the three high mill rolls according to Figs. 8 and 9 the middle roll 1a is supposed to be fixed, while the top roll and the bottom roll are adjusted by their individual stay-screws 12. The bearing box may be carried and guided by posts in fundamentally the same manner as has been described above. The post has, however, a somewhat different profile from that described above. The top roll as well as the bottom roll has a spring device 16, 17.

It is obvious that many changes may be made in the form and construction of the devices described without departing from the material principles of the invention.

Having now described my invention, what I claim as new and desire to secure by Letters Patent is:

1. A rolling mill comprising a pair of bearing blocks, a roll having end journals journalled in said bearing blocks, a second pair of bearing blocks in superposed relation to said first pair, a second roll having end journals journalled in the second pair of bearing blocks, stay screws rotatably anchored in and restrained from axial movement with respect to each of the bearing blocks of the first pair and extending therefrom through vertical bores in the bearing blocks of the second pair, internally threaded bushing members fixedly secured in the bores of said second pair of bearing blocks and engaging said stay screws to maintain the superposed bearing blocks in assembled relation, means for rotating said stay screws with respect to said bushings, rigid crossbar members secured directly to and extending between the bearing blocks of each pair to maintain the same in fixed spaced relation, a pair of stationary upright supporting standards disposed in parallel spaced relation, each of the upright supporting standards having a vertical guide flange thereon with the guide flange on one in opposed relation to and disposed in the same vertical plane as the guide flange on the other and said bearing blocks each having a vertical channel in the outer end faces thereof adapted for vertical sliding engagement with the respective opposed guide flanges on said upright standards to removably support the bearing block and roll assembly on said standards, the vertical channels in the end faces of the bearing blocks being offset to one side of the axis of the journals therein.
2. A rolling mill comprising a pair of axially aligned bearing blocks, a roll having end journals journalled in said bearing blocks, a second pair of axially aligned bearing blocks in superposed relation to said first pair, a second roll having end journals journalled in the second pair of bearing blocks, vertically extending spaced parallel stay screws mounted in and restrained from axial movement with respect to each of the bearing blocks of the first pair, said second pair of bearing blocks each having spaced parallel vertical bores therein through which said stay screws extend to mount the upper bearing blocks on the respective stay screws of the lower bearing blocks, internally threaded bushing members en-

gaging said stay screws and upper bearing blocks to maintain the superposed bearing blocks in assembled relation and to adjust the roll pressure, rigid crossbar members secured directly to and extending between the respective bearing blocks of each pair to maintain the same in fixed spaced relation, a pair of stationary upright supporting standards disposed in parallel spaced relation, each of the upright supporting standards having a vertical guide flange thereon with the guide flange on one in opposed relation to and disposed in the same vertical plane as the guide flange on the other and said bearing blocks each having a vertical channel in the outer end faces thereof adapted for vertical sliding engagement with the respective opposed guide flanges on said upright standards to removably support the bearing block and roll assembly on said standards, the vertical channels in the end faces of the bearing blocks being offset to one side of the axis of the journals therein.

3. A rolling mill comprising a self-contained removable bearing block and roll assembly unit including a pair of lower bearing blocks, a lower roll extending between said bearing blocks and having end journals, each journal mounted in the bearing of a bearing block, each of said bearing blocks having upstanding stay screws mounted thereon, an upper bearing block mounted on the stay screws of each lower bearing block, an upper roll extending between said upper bearing blocks and having end journals mounted in the bearings thereof, means threaded on said stay screws and engaging said upper bearing blocks to retain the same in position mounted on said stay screws and to adjust the roll pressure, rigid crossbar members secured directly to and extending between the bearing blocks of each pair to maintain the same in fixed spaced relation, said stay screws and cross bar members connecting said assembly in a self-contained unit, and means constituting

5 the sole support for said unit including a pair of stationary upright supporting standards disposed in parallel spaced relation, each of the upright supporting standards having a vertical guide flange thereon with the guide flange on one in opposed relation to and disposed in the same vertical plane as the guide flange on the other and said bearing blocks each having a vertical channel in the outer end faces thereof adapted for vertical sliding engagement with the respective opposed guide flanges on said upright standards to removably support the bearing block and roll assembly unit on said standards, the vertical channels in the end faces of the bearing blocks being offset to one and the same side of the axis of the journals therein, whereby said bearing blocks are unsupported at the other side of said axis.

10 20 15 20 25 30 35 40 SVEN ERIK MALTE NORLINDH.
